DESIGN FOR A TEXTILE FABRIC

Jacob Umansky, Elmhurst, Long Island, N. Y., assignor to Alexander Textile Corporation, New York, N. Y., a corporation of New York

Application August 20, 1938, Serial No. 79,469

Term of patent 3½ years

To all whom it may concern:

Be it known that I, Jacob Umansky, a citizen of the United States, residing at 80-31 Whitney Avenue, Elmhurst, L. I., in the county of Queens and State of New York, have invented a new, original, and ornamental Design for a Textile Fabric, of which the following is a specification, reference being had to the accompanying drawing, forming part thereof.

The drawing illustrates a plan view of a textile fabric showing my new design.

I claim:—

The ornamental design for a textile fabric, as shown.

JACOB UMANSKY.
